UNITED STATES PATENT OFFICE.

JOSEPH F. JONES, OF YELLOW SPRINGS, OHIO.

SAFE-ALARM.

SPECIFICATION forming part of Letters Patent No. 606,555, dated June 28, 1898.

Application filed February 27, 1897. Serial No. 625,375. (No model.)

To all whom it may concern:

Be it known that I, JOSEPH F. JONES, a citizen of the United States, residing at Yellow Springs, in the county of Greene and State of Ohio, have invented a new and useful Safe-Alarm, of which the following is a specification.

The invention relates to improvements in safe-alarms.

10 The object of the present invention is to improve the construction of safe-alarms and to provide a simple and comparatively inexpensive one which will be capable of being opened and closed only at a certain time and 15 which will start an alarm mechanism should it be disturbed by an attempt to open it surreptitiously, or to remove it bodily, or to attempt to gain access to its interior by any means.

20 The invention consists in the construction and novel combination and arrangement of parts, as hereinafter fully described, illustrated in the drawings, and pointed out in the claims hereto appended.

25 In the drawings, Figure 1 is an elevation of a safe-alarm constructed in accordance with this invention. Fig. 2 is a central vertical sectional view. Fig. 3 is a horizontal sectional view. Fig. 4 is an enlarged detail perspective view of the depressible plate and the levers for engaging the upper face of the same. Figs. 5 and 6 are detail views illustrating the construction of the time-lock. Figs. 7 and 8 are detail views illustrating the construction 30 of the combination-lock. Fig. 9 is a sectional view of the combination-lock.

Like numerals of reference designate corresponding parts in the several figures of the drawings.

40 1 designates a casing provided with a door 2 and having a clock 3 mounted in its upper portion, and the dial of the clock is arranged at the front of the casing, so that the latter presents the appearance of an ordinary clock.

45 A horizontal hasp 4 is carried by the door and extends inward therefrom and is adapted to be engaged by a sliding bolt 5. The hasp extends entirely across the casing when the door is closed and is provided at its inner end with 50 an opening for the reception of the bolt, which is supported by guides 6 when it is in engagement with the hasp. The bolt consists of a vertically-movable rod which extends upward to the clock mechanism and which is auto-

matically reciprocated by the same to lock 55 and release the door 2.

The upper end of the bolt is connected to a pivoted lever 7, which is substantially L-shaped and which is engaged by a cam 8, and the latter supports the end of the lever to 60 which the bolt is connected, the other end of the lever being fulcrumed on a suitable support. One arm of the lever 7 rests upon the cam, which is connected with a gear-wheel 9, and the latter is mounted on the main shaft 65 or arbor of the clock mechanism and receives motion from a pinion 10, which is connected with one of the shafts of the clock mechanism. The cam makes one complete revolution every twenty-four hours, and it gradually 70 increases in width in order to lift the lever 7 and raise the bolt 5. It is provided with a straight edge 11 and a curved edge 12, which extends from the inner end of the straight edge around the opposite side of the cam to 75 the outer end of the said straight edge.

As illustrated in dotted lines in Fig. 1 of the accompanying drawings, the cam is arranged so that the lever 7 will be at its highest point at six o'clock p. m. The bolt is then 80 raised out of engagement with the hasp, which will permit the door to be opened or closed when the combination-lock hereinafter described is properly manipulated. At six o'clock p. m. the door is closed, and the cam 85 permits the lever to fall and rest upon the inner terminus of the curved edge 12, whereby the bolt is carried into engagement with the hasp. This holds the door firmly locked, and during the night the lever 7 rests upon the 90 inner portion of the curved edge 12 and is not sufficiently elevated to release the hasp until six o'clock a. m., when the lever 7 reaches the high side of the cam. The lever is supported by the high side of the cam during the day, 95 and as the bolt is out of engagement with the hasp the door may be opened at any time between six o'clock in the morning and six in the evening if the combination of the lock hereinafter described is known.

100 Within the lower portion of the casing is mounted a spring-actuated alarm, which consists of a bell 13, a vibrating hammer 14, an escapement 15, and spring-actuated gearing for actuating the escapement or of the ordinary construction. The spring is mounted on a winding-shaft 16, and the escapement-shaft is provided with an arm 17, which is en-

gaged by a locking-rod 18, and the latter holds the alarm mechanism out of operation, but is adapted to be disengaged from the arm 17 to permit the alarm to ring until the spring runs down.

5 The lower end of the locking-rod, which is disposed vertically and which is mounted in suitable guides, is connected by a lever 19 with a vertically - reciprocating plunger 20, and the upper end of the locking-rod 18 is bent to form an arm, and the terminal thereof is bent at an angle and engages an eye of the arm 17. The arm of the locking-rod 18 is connected with a spiral spring 21, which assists 10 the upward movement of the rod 18 and which is designed to render the mechanism exceedingly sensitive, so that the same will respond quickly.

15 The plunger 20, which is mounted in suitable guides, carries a depressible plate 22 at its upper end which is adapted to be engaged and forced downward by levers 23, 24, and 25, whereby the alarm mechanism is thrown into operation.

20 25 The lever 23 is T-shaped and is inverted to bring its arms against the upper face of the plate 22, and the stem of the lever is fulcrumed in a substantially V-shaped support 26 and is connected with a yoke 27. The V-shaped support, which is provided at its angle with an eye 28, is secured at the terminals of its sides to the back of the casing. The yoke 24 is mounted on a horizontal rod 29, which extends from one side of the casing to 30 the other and which is connected with a lining 30, and the latter, which is rectangular, is loosely or yieldingly mounted within the lower portion of the casing and is supported by spiral springs 31 and 32. The springs 31 35 and 32 are provided with arms 33, which are secured to the back of the casing. The springs 31 are mounted on the rod 29 and the other spring 32 is disposed on a vertical rod 34, extending from the center of the horizontal rod to the top of the frame. The casing may be constructed of wood or any other suitable material, but the frame is constructed of metal or any other material that is hard enough to prevent a tool from perforating it 40 45 50 without forcing it inward. Should the frame be forced inward or downward, the lever 23 will be rocked or forced downward, thereby depressing the plate 22 and setting the alarm mechanism into operation.

55 60 65 The lever 24, which is provided with a pair of substantially L-shaped arms 35, is fulcrumed on a substantially U-shaped support 36 and is connected by a spring 37 with the back of the casing, whereby when the spring is free to operate the lever will be drawn rearward, forcing its arms 35, which are disposed horizontally, downward and depressing the plate 22. The lever 24 carries an arm or rod 38, which extends rearward into an opening 39 of the back of the casing and which is adapted to be engaged by a plug 40. The plug 40, which is preferably provided

with a threaded shank, is mounted on and projects outward from the wall against which the casing is placed, and it projects into the opening 39 and holds the lever 24 against backward movement while the casing is in proper position; but should an attempt be made to rob the casing and the same should be moved forward the spring 37 will operate 70 75 to start the alarm mechanism as soon as the casing leaves its position against the wall.

The casing is provided at its bottom with an opening 41, into which projects a plug 42, similar to that just described, and it engages 80 the lower end of a vertically-disposed rod 43, which extends downward from the detachable plate to the bottom of the casing. The upper end of the rod 43, which is arranged in a suitable guide or support 44, is secured to 85 the depressible plate, and it is engaged by a coiled spring 45, disposed on it, engaging the guide or support 44 at the bottom thereof and adapted to force the rod 43 downward should the casing be lifted from the shelf 46 or other 90 suitable support upon which the casing is placed.

95 The lever 25 is provided with a rearwardly-extending arm 47^a and a pair of substantially L-shaped arms 47, which extend forward from the support 36, upon which the lever 25 is fulcrumed, and the upper portion of the lever is connected with an oscillating frame 48 and when swung forward by the means hereinafter described depresses the plate 22 and throws 100 the alarm mechanism into operation. The oscillating frame 48 consists of a stem, which is fulcrumed at its lower end on the bottom of the casing, and a substantially rectangular loop 49, which is adapted to be engaged by 105 reciprocating bolts 50 of a combination-lock 51. The loop is provided at its upper portion with an arm, which is secured to the lever 25, and if the door is forced outward an alarm will be given.

110 The reciprocating bolts 50, which are arranged parallel with each other, are mounted in a horizontal guide 52 at the inner face of a door-lining 53, and the opposite faces of the bolts are provided with teeth, forming racks 115 and meshing with a pinion 54. The pinion 54, which is provided with a sleeve 54^a, is arranged on a spindle 55^a of a knob 55, located on the exterior of the door. The spindle of the knob carries a spring 55^b, which engages 120 frictionally the adjacent end of the sleeve with sufficient force to cause the pinion 54 to rotate with the knob and reciprocate the bolts 50. The knob carries an index-finger 125 56, which operates in conjunction with a dial or plate 57, that is provided with a series of numbers or marks to enable the operator to manipulate the rack-bars and arrange them in the position illustrated in Fig. 1 of the accompanying drawings when it is desired to 130 open the door. Either end of each rack-bar may be engaged with the loop of the movable frame 48, and when the bolts are out of engagement with the said loop the pinion en-

gages them at their centers. The rotation of the pinion is limited by the length of the racks of the bolts, and should the knob be rotated as much as possible in either direction the operation will extend the bolts and position them so as to engage the loop. Any outward movement of the door when the bolts are in engagement with the loop serves to ring the alarm.

10 By connecting the spindle of the knob in the manner described the knob may be rotated freely after the pinion has reached the limit of its rotation and the bolts have been reciprocated to the end of their movement.

15 A person unfamiliar with the combination will receive no intimation of the position of the bolts after they have reached the limit of their movement, as the knob may be continuously rotated, and it will be impossible for 20 the person to open the door without knowing the correct combination. A person who understands the combination by rotating the knob continuously in either direction will know that the bolts are in their extended position and can then manipulate the knob to 25 open the door.

The lining 53 of the door is metallic and is mounted yieldingly on horizontal bolts or pins 58 and has springs 59, engaging its inner and 30 outer faces. Should the lining 53 of the door be forced inward, the lever 25 will be rocked rearward to carry its arm 47^a into engagement with the compressible plate 22 and cause the latter to throw the alarm mechanism into 35 operation.

The casing is provided with suitable receptacles 60, adapted to contain valuables, and these receptacles may be of any preferred construction.

40 It will be seen that the safe-alarm is positive and reliable in operation and that the alarm mechanism will be thrown into operation should the safe be tampered with. It will also be apparent that the alarm mechanism will be thrown into operation should the casing be moved from its shelf or support in an attempt to carry it off, and the spring of the alarm mechanism is designed to be of sufficient length to cause the bell to ring a 45 considerable length of time, so that should it be stolen the alarm will continue ringing while the thief is traveling three or four squares or more.

Changes in the form, proportion, and minor 50 details of construction may be resorted to without departing from the spirit or sacrificing any of the advantages of this invention.

What I claim is—

1. In a device of the class described, the 55 combination of a casing having a door, a lock provided with a bolt, a rotary cam connected with the clock mechanism, and a lever connected with the bolt and resting upon and raised by the cam and adapted to fall and 60 actuate the bolt when released by the said cam, substantially as described.

2. In a device of the class described, the combination of a casing having a door, a hasp carried by the door, a vertically-movable bolt mounted on the casing and arranged to engage the hasp when the door is closed, and a rotary cam connected with and operated by the clock mechanism and supporting the bolt, 70 said cam being provided at one side with a straight edge and having a curved edge extending from the inner end of the straight edge around the other side of the cam to the outer end of the straight edge, substantially as described.

3. In a device of the class described, the 75 combination of a spring-actuated alarm having an escapement, means for holding the latter normally out of operation, a plunger connected with such means and provided with a compressible plate and adapted to actuate the 80 said means for releasing the alarm, levers engaging the compressible plate, and means for operating the levers to depress the plate, substantially as described.

4. In a device of the class described, the 85 combination of a casing, an alarm mechanism, a reciprocating locking-rod holding the alarm mechanism normally out of operation, a lever connected with the locking-rod, a plunger connected with the lever, and means for reciprocating the plunger to actuate the locking-rod and lift the same out of engagement with the alarm mechanism, substantially as described.

5. In a device of the class described, the 90 combination of a casing, an alarm mechanism, means for holding the alarm mechanism normally out of operation, a spring-actuated rod arranged to engage the support upon which the safe is mounted, and connections 95 between the rod and the means for holding the alarm mechanism out of operation, whereby the alarm mechanism will be thrown into operation when the casing is moved, substantially as described.

6. In a device of the class described, the 100 combination of a casing, an alarm, a locking device holding the alarm normally out of operation, a reciprocating plunger connected with and adapted to release the locking device, a spring-actuated lever engaging the plunger, and an arm or rod connected with the lever and adapted to hold the same out of engagement with the plunger when the casing 105 is in position on its support, substantially as 110 and for the purpose described.

7. In a device of the class described, the 115 combination of a casing, an alarm mechanism, a locking device holding the alarm mechanism normally out of operation, a spring-actuated rod connected with the locking device and adapted to disengage the same from the alarm mechanism, said rod having its outer end arranged at an opening of the casing, and a plug projecting into the said opening 120 engaging the rod and adapted to maintain the spring in its depressed position when 125 130

the casing is in its normal position, substantially as described.

8. In a device of the class described, the combination of a casing, an alarm mechanism, a locking device maintaining the alarm mechanism normally out of operation, a yieldingly-mounted lining arranged within the casing, and connections between the lining and the locking device, whereby the latter will be thrown out of engagement with the alarm mechanism should an attempt be made to perforate the casing, substantially as described.

9. In a device of the class described, the combination of a casing, an alarm mechanism, a locking device holding the alarm mechanism normally out of operation, a lining arranged within the casing, rods connected with the lining, springs secured to the casing and to the rods and yieldingly supporting the lining, and connections between the rods and the locking device whereby the latter is thrown out of engagement with the alarm mechanism when the lining is moved, substantially as described.

10. In a device of the class described, the combination of a casing, an alarm mechanism mounted in the casing, a locking device holding the alarm mechanism normally out of operation, a movable lining arranged in the casing, a plunger provided with a depressible plate and connected with the locking mechanism, rods carried by the lining, and a lever fulcrumed on a suitable support connected with the rods and arranged to engage the depressible plate, substantially as described.

11. In a device of the class described, the combination of a casing, an alarm mechanism, a locking device holding the alarm mechanism normally out of operation, a depressible plate connected with the locking mechanism, a T-shaped lever fulcrumed on a suitable support and having its arms engaging the depressible plate, whereby the latter is operated when the lever is swung in either direction or is forced downward, a movable lining, rods connected with the lining, and a yoke mounted on the rods and receiving the upper end of the lever, substantially as described.

12. In a device of the class described, the combination of a casing, an alarm mechanism, a locking device for holding the alarm mechanism out of operation, a depressible plate connected with the locking device, a lever arranged to engage the depressible plate, and a lock mounted on the door of the casing and connected with the lever, substantially as described.

13. In a device of the class described, the combination of a casing, an alarm mechanism, a locking device for holding the alarm mechanism normally out of operation, a loop connected with and adapted to disengage the locking device from the alarm mechanism when it is drawn outward, and a combination-

lock provided with reciprocating bolts engaging the loops, substantially as described.

14. In a device of the class described, the combination of a casing, an alarm mechanism, a locking device for holding the alarm mechanism out of operation, a depressible plate connected with the locking mechanism, an oscillating frame provided with a loop, a lever connected with the frame and arranged to engage the depressible plate, and a lock engaging the loop, substantially as described.

15. In a device of the class described, the combination with a casing, of a pair of reversely-reciprocating bolts mounted in the casing and extending from both sides thereof when in their locked position, said bolts being provided between their ends with teeth, a pinion interposed between the reciprocating bolts, meshing with the teeth thereof and capable of rotation in either direction to reciprocate the bolts to a locked position, a knob, and means for connecting the knob with the pinion, said means frictionally engaging one of said parts, whereby the knob is adapted to rotate the pinion sufficiently to lock the bolts and is capable of further rotation independently of the pinion, substantially as described.

16. In a device of the class described, the combination with a pair of reciprocating bolts provided with teeth, a pinion interposed between and meshing with the teeth of the bolts, a knob or stem connected with the pinion for rotating the same, and provided with a suitable index or pointer, and a stationary dial, substantially as described.

17. In a device of the class described, the combination of a casing provided with a door, an alarm mechanism mounted in the casing, a locking device for holding the alarm mechanism normally out of operation, a movable lining mounted on the inner face of the door, a plunger having a depressible plate and connected with the locking device, a lever fulcrumed on a suitable support and provided with arms extending in opposite directions and engaging the depressible plate, and connections between the door and the lever whereby the alarm mechanism will be thrown into operation when the door is drawn outward or the lining is forced inward, substantially as described.

18. In a device of the class described, the combination of a pair of reciprocating bolts provided with teeth, a pinion interposed between the bolts and meshing with the teeth thereof, the knob having a spindle loosely receiving the pinion, and a spring mounted on the spindle and engaging the pinion frictionally, substantially as described.

In testimony that I claim the foregoing as my own I have hereto affixed my signature in the presence of two witnesses.

JOSEPH F. JONES.
